FIG. 2.

FIG. 1.

FIG. 3.

FIG. 5.

FIG. 4.

FIG. 6.

FIG. 7.

INVENTOR:
FREDERICK C. OVERBURY

By
John Brown, Secretary

ATTYS.

UNITED STATES PATENT OFFICE.

FREDERICK C. OVERBURY, OF HILSDALE, NEW JERSEY, ASSIGNOR TO THE FLINT-KOTE COMPANY, OF BOSTON, MASSACHUSETTS, A CORPORATION OF MASSACHUSETTS.

ROOF.

Application filed December 22, 1921. Serial No. 524,104.

This invention relates to roofs, more particularly of that type composed of sheet material such as is commonly formed of fibrous material impregnated or coated with asphalt, with or without a surface coating of ground slate or similar granular material to provide a weather-resisting surface of pleasing color. One of the objections heretofore urged against such roofing has been that even though the material is cut in the shape of shingles or strips which may be laid in overlapping courses the comparative thinness of the material causes the roof to appear thin and cheap.

This invention provides a construction by which this objection is obviated and by which if desired a variegated effect may be produced in patterns simulating different forms of tiles or similar heavy, substantial and highly ornamental construction.

For a more complete understanding of this invention reference may be had to the accompanying drawings in which

Figure 1 is a plan of a portion of sheet roofing which may be formed in accordance with this invention.

Figure 2 is a perspective of the sheet partly formed into a completed panel.

Figure 3 is a plan of a completed panel or roof section.

Figures 4 and 5 are views similar to 1 and 3 showing a different design.

Figure 6 is a perspective similar to Figure 2, but showing a modified construction.

Figure 7 is a view similar to Figure 6 showing a further modification.

Referring to the form shown in Figures 1, 2, and 3, a strip of roofing material as 1 is formed with pairs of fold lines 2 and 3 about which the material may be bent on itself in opposite directions. Extending upwardly from the fold line 2 the portion 4 which forms the outer surface of the completed panel is formed with cut-outs 5, these cut-outs preferably terminating at the fold line 2 but may, if desired, be carried there-around or placed thereabove. The strip 1 is then folded in the manner shown in Figure 2, portions 4 forming the upper faces of overlapping courses, the portions 6 forming the lower faces of these courses. Between the folds may then be placed pieces of sheet material 7 to extend down substantially to the fold lines 2 so that the ma-

terial thereof may show through the cut-outs and present therewith a pattern when the folds are brought close together in the manner shown in Figure 3. If desired the inserted sheets 7 may be of contrasting colors to the surface of the folded sheet so as to produce a variegated color effect.

In Figures 4 and 5 is shown a similar construction of folded material but in which the cut-outs 50 are of different shape to show a different pattern when the panel is formed as shown in Figure 5. While the fold lines have been shown as extending laterally of the sheet, it is evident that they could be made longitudinal if desired, the sheets being cut in appropriate lengths.

Instead of forming the roof in panels it may be formed of superposed single strips as shown in Figure 6, each strip comprising an outward section 40 and a back section 60 folded about a fold line 20. Between the portions 40 and 60 may be inserted a strip 70 which, if desired, may be of a different color from the folded strip so that when the strips are assembled a pattern of variegated color may be presented similar to the construction shown in Figures 3 and 5.

As a further modification the lower edge of the inserted strip 70 may be cut out or notched as shown at 71 in Figure 6 to show the surface of the underlying folded portion to present an additional variegated form to the pattern. The portion 71 may be such that the inner edge of the cut-out of the portion 40 is merely bordered by the color presented by the inserted sheet or an entirely different pattern may be formed thereon as desired.

In Figure 7 is shown a construction wherein the inserted sheet is notched to form tabs 72 which project below the fold line 20 simulating the lower ends of rectangular tiles or shingles, this construction as shown being merely a modification of that of Figure 6. A similar construction might, however, be applied to the panel construction illustrated in Figures 1 to 5. It will be seen that with the construction shown it is possible to obtain a great variety of patterns and color effects and that the thickness of exposed edges of the roofing units may be varied from one to three thicknesses of the sheet material of which

they are composed so as to vary the extent of actual relative relief of the various portions.

Having thus described certain embodiments of this invention it should be evident that many changes and modifications might be made therein without departing from its spirit or scope as defined by the appended claims.

10. I claim:

1. A panel composed of a sheet folded alternately in opposite directions, the outwardly facing portions having designs cut out therefrom, and a sheet placed between the 15 folds and showing through said cut-outs.

2. A panel composed of a sheet folded alternately in opposite directions, the outwardly facing portions having designs cut out therefrom, and sheets placed between the 20 folds and showing through said cut-outs, said folded and other sheets being of different colors.

3. A panel composed of a sheet folded alternately in opposite directions, the outwardly facing portions having designs cut out therefrom, and sheets placed between the 25 folds and showing through said cut-outs, said last mentioned sheets having cut-outs through which the surface of the underlying 30 folded portion is visible.

4. A panel composed of a sheet folded alternately in opposite directions, each outwardly facing portion having cut-outs extending from the line of fold with its adjacent underlying portion, and sheets notched at their edges placed between the 35 folds, the notched edges appearing through said cut-outs.

5. A roof comprising a series of overlying 40 courses, each course comprising a portion of sheet material folded back on itself, and a piece of sheet material inserted between the folds, the outwardly facing parts of said folded material having cut-outs through 45 which the inserted sheet is visible.

6. A roof composed of a series of overlying courses, each course comprising a portion of sheet material folded back on itself, and a piece of sheet material of different 50 color than said folded material inserted be-

tween the folds a portion of said piece being visible.

7. A roof composed of a series of overlying courses, each course comprising a portion of sheet material folded back on itself, and a piece of sheet material inserted between the folds, the outwardly facing parts of said folded material having cut-outs extending from the line of fold. 55

8. A roof composed of a series of overlying courses, each course comprising a portion of sheet material folded back on itself, and a piece of sheet material of different color than said folded material inserted between the folds, the outwardly facing parts 60 of said folded material having cut-outs through which the inserted sheet is visible. 65

9. A roof composed of a series of overlying courses, each course comprising a portion of material folded back on itself, and a piece of sheet material inserted between the folds, the outwardly facing parts of said folded material having cut-outs through 70 which the inserted sheet is visible, said inserted material being cut along its lower edge to form a pattern with said cut-outs. 75

10. A roof composed of a series of overlying courses, each course comprising a portion of sheet material folded back on itself, and a piece of sheet material of different 80 color than said folded material inserted between the folds, the outwardly facing parts of said folded material having cut-outs through which the inserted sheet is visible, said inserted material being cut along its 85 lower edge to form a pattern with said cut-outs. 90

11. A roofing element comprising a piece of sheet material folded on itself and having cut-outs in its outer layer, and a piece of sheet material inserted within the fold and visible through said cut-outs. 90

12. A roofing element having exposed areas of different colors arranged according to a predetermined pattern, said element also 95 having exposed edges presenting portions of three different thicknesses.

In testimony whereof I have affixed my signature.

FREDERICK C. OVERBURY.
